C. W. FRENTZ.
SEWING BOX.
FILED AUG. 26, 1922.

INVENTOR

Charles W. Frentz,
BY
Arthur M. Hood.
ATTORNEY

UNITED STATES PATENT OFFICE.

CHARLES W. FRENTZ, OF INDIANAPOLIS, INDIANA.

SEWING BOX.

Application filed August 26, 1922. Serial No. 562,454.

To all whom it may concern:

Be it known that I, CHARLES W. FRENTZ, a citizen of the United States, residing at Indianapolis, in the county of Marion and State of Indiana, have invented a new and useful Sewing Box, of which the following is a specification.

My invention relates to improvements in work holders or sewing boxes and more particularly to the means for supporting a plurality of spools of cotton, yarn, or the like whereby the spools or rolls may be supported in a manner which will permit the convenient unwinding of the material as it is being used.

For the purpose of disclosing my invention I have illustrated certain embodiments of the invention in the accompanying drawing in which;

20 Fig. 1 is a perspective view of a sewing box embodying my invention;

Fig. 2 is a sectional view of the same;

Fig. 3 is an enlarged detail of the spool supporting rod socket;

25 Fig. 4 is a plan view of the structure illustrated in Fig. 3.

Fig. 5 is a detailed view of the supporting end of the spool receiving rod, and

30 Fig. 6 is a perspective view of a separate base for the center post.

In the embodiment of the invention illustrated I preferably provide a box or receptacle 1 which may take any suitable form but is illustrated as being rectangular in shape and is divided into a series of compartments 2, 3, and 4, by a pair of dividing walls 5 and 6. The compartment 2 preferably extends the entire length of the receptacle, while compartments 3 and 4 are only about one half the length of compartment 2. The box or receptacle is provided with a suitable hinged cover 7 which on its lower face is provided with a series of loops 8 to receive various sewing implements, such as 35 scissors 9 and the like.

In one of the compartments, preferably compartment 4, I arrange a spool holder for a number of spools of thread. This holder comprises a base 10 which is removably fitted in the compartment and is provided with a series of spool pins 11 extending vertically therefrom. The spools are mounted on these pins and the thread from the spools is led out through openings 12 40 in one of the side walls of the receptacle

so that the thread may be readily taken off from the spool without becoming entangled and without necessity of raising the lid of the receptacle. This compartment 4 is also adapted to be closed by a suitable lid 13 60 hinged on to the wall 5 and this lid is provided on its under face with a suitable cushion 14 for pins or needles. For the purpose of supporting various spools of thread, yarn, or the like to enable the same to be 65 readily unwound, I provide a center post 15 which at its upper end is provided with a table 16 from which extends a plurality of supporting spindles or rods 17 adapted to receive the spools of yarn or thread. These 70 rods or spindles are preferably provided at their outer ends with removable heads 18 to permit the mounting thereon of yarn spools 19. The rods at their inner ends are provided with T heads 20 arranged to be 75 inserted into suitable sockets formed in the table 16. As shown in Figs. 2, 3, and 4 the table preferably comprises a flat upper plate 21 around the outer periphery of which is arranged a downwardly extending flange 80 22. On the under side of the plate 21 I provide a series of cross ribs 23. The plate 21 at suitable intervals has formed therein an elongated slot 25 which is intersected by a transversely extending slot 26, the slot 26 85 being sufficiently wide to permit the insertion therein of the head 20. The flange 22 at a point opposite slot 25 is provided with a slot 27 corresponding in width to slot 25 and each of the ribs 23 at a point beneath 90 the slot 25 is cut away as at 28 a distance equal to the length of slot 26.

The above socket arrangement permits of the mounting of the spindles 17 in either a vertical or horizontal position. If it is desired to mount the spindle in a vertical position the T head 20 which is flattened and has a substantial width is first inserted in the slot 26 with the spindle 17 extending in a horizontal position. Slot 27 permits the T 100 head to drop below the surface of plate 21 and spindle 17 may then be rotated to a vertical position with the head 20 substantially parallel with the plate 21. By sliding head 20 back under the plate 21 to a position where the head fits in the cut-away portion 28 of the rib, the spindle 17 will be supported vertically as indicated in Fig. 2.

If it is desired to support the spindle in a horizontal position the head, after being 110

inserted as above described is moved further inwardly until it clears rib 23, after which the spindle may be turned downwardly into a horizontal position and the spindle will be locked against displacement. The post 15 is removably mounted in position and to support it in its vertical position I provide a bolt 29 which may be passed through the post and through the wall 5, a wing nut 30 being adapted to engage the bolt on the opposite side of the wall and thereby clamp the post to the wall.

The compartment 2 is preferably extended the entire width of the box or receptacle so that when the post and supporting spindle 17 are disassembled they may be stored in the compartment.

To permit the use of the supporting post 15 and its associated parts independently of the box, I provide a separate base 31 which is socketed to receive the lower end of the post and is provided with a vertically extending plate or brace 32 to which the post may be bolted in the same manner as it is fastened in the box or receptacle.

I claim as my invention:—

1. In a sewing box, the combination with a receptacle, of a spool support comprising a central post, a table supported on said post, said table having a plurality of sockets, and a plurality of spool spindles having means removably engaging in said sockets.

2. In a sewing box, the combination with a receptacle, of a supported post removably secured in position in said receptacle, a table supported on said post and having a plurality of sockets formed therein and a plurality of spool supporting spindles having

means arranged to engage in said sockets to permit said spindles to be supported in either a vertical or horizontal position.

3. In a sewing box, the combination with a suitable receptacle, of a spool support mounted therein comprising a central post, a table mounted on said post, said table having a T shaped slot formed therein and a spool supporting spindle having a T head arranged to be inserted in the transverse portion of said T slot and engaged beneath the table to support said spindle in work holding position.

4. In a sewing box, the combination with a receptacle, of a spool holder support comprising a central post removably supported by said receptacle, a table secured at the upper end of said post having means for removably securing to said table a plurality of spool supporting spindles and a second spool support comprising a base having a plurality of vertically extending spool supporting spindles and arranged in said receptacle, said receptacle having a plurality of thread openings in side wall thereof.

5. In a spool holder for sewing and the like, the combination with a suitable base, of a supporting post removably mounted on said base, a table mounted at the upper end of said post having a plurality of sockets and a plurality of spool receiving spindles each having means for engaging said sockets to permit the spindles to be mounted in either a vertical or horizontal position.

In witness whereof I, CHARLES W. FRENTZ, have hereunto set my hand at Indianapolis, Indiana.

CHARLES W. FRENTZ.
